UNITED STATES PATENT OFFICE.

HENRY RUPPEL, OF CLEVELAND, OHIO, ASSIGNOR TO THE Dangler
STOVE AND MANUFACTURING COMPANY.

TANK FOR GASOLINE OR VAPOR STOVES.

SPECIFICATION forming part of Letters Patent No. 497,896, dated May 23, 1893.

Application filed July 7, 1892. Serial No. 439,204. (No model.)

To all whom it may concern:

Be it known that I, HENRY RUPPEL, a citizen of the United States, residing at Cleveland, in the county of Cuyahoga and State of Ohio, have invented a certain new and Improved Tank for Gasoline or Vapor Stoves, of which the following is a full, clear, and complete description.

My improved tank for gasoline or vapor stoves, relates to an outer and inner tank the outer one of said tanks being provided with a false bottom having a central opening therein which may be closed by a spring actuated disk and the bottom of the said inner tank being provided with a collar to which is attached a plug and a spring actuated valve.

The object of my invention is to provide a tank so constructed and arranged as to regulate and govern the supply of oil to the burner and also to prevent explosion and insure safety in case of accident, as when a stove is upset, by cutting off at once the flow of oil and confining the same to the inner tank.

That my invention may be seen and fully understood by others, reference will be had to the following specification and annexed drawings forming a part thereof.

Figure 1 is a vertical section of the two tanks connected; Fig. 2 a vertical section of the tanks disconnected; Fig. 3, a smaller horizontal section of the outside tank above the false bottom; Fig. 4, a full size view of the plug and valve, showing the method by which the valve stem is held in place. Fig. 5, represents a small stove or heater, with my tank attached thereto, and connected with the burner. Fig. 6, is a partial view of a gasoline cook stove with my tank attached thereto and connected with the burner.

Similar letters of reference designate like parts in the drawings and specification.

The outer tank A is provided with the false bottom B Figs. 1, 2, and 3 forming a tight joint with said tank. The opening B', is centrally located in the false bottom B and is closed in Fig. 2, by the concavo-convex disk C, which is attached to the upper part of the tube D.

In the disk C is the opening C' corresponding in size to the inner diameter of the tube D. The tube D Figs. 1, 2 and 3 fits closely over the tube E, which is secured to the bottom of the tank A, and has at its base the

openings E'. The spiral spring F Figs. 1 and 2 encircling the tubes D and E and bearing 55 at its base upon the bottom of the tank A, and at its top on the under or concave surface of the disk C, forces said disk tightly against the false bottom B, when there is no preponderance of pressure from above, as shown in 60 Fig. 2, thereby closing the opening B'.

The pin G, Figs. 1, 2 and 3 is held rigidly in the center of the tube E by the small pins G'.

In the center of the bottom of the tank A, is an opening to receive the pipe H, which 65 carries the gasoline to the burner.

The tank A is provided with the cover A', and the spring I Figs. 1, 2, which prevents the cover A' from being opened more than is sufficient to remove or replace the inner tank 70 and as will be seen in Fig. 2, the cover must always drop into place over the top of said tank by its own weight unless otherwise held up. The cover A' has the handle A², with which to raise said cover.

In the drawings the false bottom B has on its upper surface, an annular ridge a. Fig. 3 surrounding the opening B' and the ribs b Figs. 1, 2, and 3 radiating from the ridge a. to the outer circumference of the false bottom. 80

In the side of the tank A and a little below the false bottom B is the small opening J. Figs. 1 and 2, through which air is admitted after passing in at the top of the tube J', said tube extending from below the opening 85 J. on the outside of the tank A to within a short distance of the top of said tank.

The heaviest part of a gasoline stove is the back, and a stove when upset generally falls backward. For this reason the tube J' is 90 placed preferably on the front of the tank so that no oil will escape through it in case of accident.

The inner tank K Figs. 1 and 2 has a closed top which is provided with the handle K' for 95 raising the inner tank out of the outer one, or lowering it into the same.

Within a central opening in the bottom of the tank K is secured the collar L Figs. 1 and 2, the lower part of which is screw threaded 100 on the inside, to receive the plug M which forms a tight joint with the nozzle L by means of the washer N. At intervals around the base of the plug M are the knobs M', for the purpose hereinafter described.

The plug M is provided with a valve open-

ing O, said opening being closed by the valve P, as illustrated in Fig. 2.

The guide Q consisting of two angular shaped pieces of metal (best shown in Fig. 4) secured at their base in an annular groove surrounding the opening O in the plug M, has a hole in the top through which the valve stem P' passes. The spiral spring R, is interposed between the top of the valve P, and the 10 under surface of the top of the guide Q and forces the valve upon the seat M², as in Fig. 2 when there is no pressure from below upon said valve; thereby completely closing the valve opening O, thus cutting off the flow of 15 gasoline from the tank K.

In operation, the tank K, having been filled with oil is lowered into the tank A until the knobs M', come in contact with the upper or convex surface of the disk C and the top of 20 the pin G strikes against the base of the valve P, when the weight of the tank K and its contents forces the disk C, and tube D, down until the tank K rests upon the false bottom; at the same time the valve P is 25 opened by the pin G, when the several parts will appear as shown in Fig. 1. The result of this condition of the parts is, that the fluid in the tank K, flows through the opening O in the plug M and out through the interstices 30 formed by the plug M, knobs M' and the disk C into the space below the false bottom B, filling the same as high as the dotted lines x x Fig. 1. Since air is admitted below the false bottom through the tube J' and the opening 35 J, the liability of explosion of the fluid contained in the tank is reduced to a minimum by preventing the liquid from rising above the lines x, x. The oil now runs into the pipe H through the openings E', in the tube E and 40 is thence conveyed to the burner. More or less of the oil will flow directly into the pipe H through the tube E. When the tank K is empty and it is lifted out or in case the stove, to which it is attached is overturned accidentally, as often happens, and the two tanks become disconnected, the spring R will close the valve P, thus cutting off the supply of oil 45 from the tank A, and the spring F will raise the disk C into place; thereby closing the opening B', in the false bottom B through 50 which the plug and collar were obliged to pass.

The herein described tank may be used in connection with the burner S, Fig. 5 to heat 55 a small stove or heater T, or it may be used in connection with the burner S'. Fig. 6 in the cook stove T'. The flow of oil from the tank to the burner S or S' through the pipe U or U' is controlled by a valve V, said valve being provided with the safety latch W Figs. 5 and 6. A partition of asbestos Y Figs. 5 and 6 separates the tank from the stove to prevent the generation of gas, by reason of the contents of said tank becoming heated. Any 65 other non-conductor of heat may be used as a substitute for asbestos. The pin G Figs.

1, 2 and 3 may be omitted and the tube E lengthened sufficiently to perform the office of said pin, in raising the valve P. When the tank K is removed from the outer tank 70 to be refilled, it is reversed and the plug with the several parts attached thereto, is unscrewed, which permits the oil to be turned in through the opening in the collar L Figs. 1 and 2.

This tank is designed to be used with a suitable burner for the consumption of hydro-carbon fluid.

What I claim as my invention, and desire to secure by Letters Patent, is—

1. In a tank for gasoline or vapor stoves, an inner tank having a collar attached to the bottom thereof, interiorly screw threaded at its lower part to receive a plug, said plug being provided with knobs M', and having an 85 annular opening closed by a spring actuated valve, held in place by a valve-stem supported by the guide Q, in combination with an outer tank having a false bottom provided with a central opening closed by a spring actuated 90 disk in connection with the tube D, outside of the tube E, said tube E having lateral openings in the base and a pin G, attached thereto in the manner substantially as and for the purpose set forth.

2. In a tank for gasoline or vapor stoves, an inner tank having a collar, plug and spring actuated valve attached to the bottom thereof in combination with an outer tank having a false bottom, with a central opening closed 100 by a spring actuated disk, a tube E, and pipe H, the cover and spring I in the manner substantially as and for the purpose set forth.

3. In gasoline or vapor stove tanks, the false bottom B, having a central opening, closed by 105 a spring actuated disk in connection with the pipes D and E, said pipe E having a pin in the center thereof and provided with the openings E', at the base, in combination with a threaded collar and plug, attached to the 110 bottom of a tank having a central opening closed by a spring actuated valve in the manner substantially as and for the purpose set forth.

4. In a tank for gasoline or vapor stoves, 115 an outer tank incased in a non-heat-conducting substance and having a false bottom provided with a central opening closed by a spring-actuated disk, the tube D, perforated tube E, pin G and the pipe J', in combination with 120 an inner tank having a collar and plug attached to the bottom thereof, said plug being provided with an annular opening closed by a spring-actuated valve, in the manner substantially as and for the purpose set forth.

In testimony whereof I affix my signature in presence of two witnesses.

HENRY RUPPEL.
